Primary Examiner—Stella M Reid*Assistant Examiner*—Elizabeth J Oswecki(74) *Attorney, Agent, or Firm*—Plumsea Law Group, LLC(57) **CLAIM**

The ornamental design for a footwear cleat plate, as shown and described.

DESCRIPTION

FIG. 1 is a bottom perspective view of a footwear cleat plate showing my new design;

FIG. 2 is a bottom plan view thereof;

FIG. 3 is a lateral side elevational view thereof;

FIG. 4 is a medial side elevational view thereof;

FIG. 5 is a front elevational view thereof;

FIG. 6 is a rear elevational view thereof; and,

FIG. 7 is a top perspective view thereof.

The broken line showings of the shape in FIGS. 1 and 2 are not part of the claimed design. The top surface of the plate depicted without shading in FIGS. 3–7 is not part of the claimed design.
